METHOD OF AND APPARATUS FOR GAS ANALYSIS

Arthur C. Jenkins, Kenmore, N. Y., assignor to
The Linde Air Products Company, a corpora-
tion of Ohio

Application December 2, 1938, Serial No. 243,496

12 Claims. (CL 23—232)

This invention relates to a method of and apparatus for gas analysis, and more particularly to a method of and apparatus for indicating continuously the oxygen content in a given atmosphere and intermittently the carbon dioxide content in said atmosphere with a single apparatus.

In the practice of oxygen therapy, a simple and reliable means for indicating the oxygen and carbon dioxide concentrations in the atmosphere of oxygen rooms, oxygen tents, etc., is a practical necessity, both in order to insure the maintenance of the correct proportions of these gases in the atmosphere and to prevent undue waste of oxygen.

Various types of analyzers heretofore used in this field have not proven satisfactory. Among other disadvantages, such analyzers are capable of only intermittent determination of the oxygen concentration. These separate determinations require the frequent handling of chemical solutions, which factor may be a source of danger to inexperienced persons. While analyzers have been constructed which will continuously indicate the oxygen concentration, these analyzers can not be used to determine the carbon dioxide concentration without seriously affecting the calibration of the analyzer and hazarding a serious disruption of the delicate and sensitive component elements of the analyzer.

In one type of apparatus used heretofore for gas analysis, the gas to be analyzed and a standard gas, which may be air, are passed respectively through two tubes so constructed and arranged that the composition of the gas under analysis can be determined through comparison of pressures existing at certain points in each of the respective tubes. This apparatus, while somewhat more satisfactory than intermittently operating analyzers, is incapable of alternately determining the concentration of more than one element in the gas under analysis without the disadvantageous phenomena set forth above.

It is therefore among the objects of this invention to provide a method of and apparatus for continuously, directly, accurately and rapidly indicating the concentration of one constituent in a given atmosphere; which apparatus is readily convertible to indicate similarly the concentration of another constituent of said atmosphere; in which apparatus the indications are dependent only upon the physical properties of the gas being analyzed; which apparatus may be converted readily to indicate either oxygen concentration or carbon dioxide concentration without affecting

the calibration of the apparatus or hazarding disruption of its component parts; which method and apparatus do not require the frequent handling of chemical solutions; and which apparatus is portable, simple to operate and relatively inexpensive to manufacture and the indications of which are unaffected by humidity.

These and other objects of the invention will in part be obvious and in part become apparent from a consideration of the following description and accompanying drawing, in which:

Fig. 1 diagrammatically illustrates the general arrangement of the apparatus;

Fig. 2 is a longitudinal sectional view through a valve used to adjust the apparatus; and

Fig. 3 is a longitudinal sectional view of a two-way valve used to convert the apparatus to indicate either the oxygen or the carbon dioxide concentration without interrupting the flow of gas through the apparatus.

In the embodiment of the invention illustrated in the drawing, the gas to be analyzed and a standard gas, such as air, are drawn through a gas comparing means or analyzer comprising a viscosity-effusion bridge B by means of a suitable exhausting apparatus or means such as a vacuum pump P, shown diagrammatically. The bridge comprises a pair of capillary comparison tubes C, C' each connected, on the down-stream side, by T-pieces T, T' to orificed plates formed with orifices O, O' and mounted in an evacuating chamber E connected to the vacuum pump. Also connected to each T-piece is a differential manometer M, the liquid level of which, in cooperation with a suitable scale S, indicates the concentration of oxygen or carbon dioxide in the gas undergoing analysis.

The operation of the apparatus is based on the physical laws governing the flow of gases through orifices and capillary tubes. The rate of flow of gas through an orifice varies inversely as the square of the gas density, while the rate of flow of gas through a capillary tube is a function of the gas viscosity. Due to these properties of gases, there is a definite pressure drop through the capillaries C and C' and through the orifices O and O', when any particular gas is drawn through the bridge. Thus, if the same gas is drawn simultaneously through each side of the bridge, and both sides have the same dimensions, the pressures in the T-pieces T, T' will be equal, and the liquid level in each arm of the differential manometer M will be at the same elevation.

If now, a standard gas, such as air or any other gas whose composition is known or prede-

terminated, is drawn through the right hand capillary tube C' and a sample gas having a density or viscosity or both different from that of air is drawn through the capillary tube C, the pressures in the respective T-pieces will be unequal, and the liquid in the manometer M will rise to a greater height in one arm of the manometer than in the other arm. The gases should enter the capillary tubes at atmospheric pressure or at equal pressures approximately atmospheric. By suitable calibration of the scale S, and with the use of other elements of the apparatus described hereinafter, the liquid level may be used to compare the respective viscosities and densities of the gases and thus indicate the percentage concentration of one or more elements of the sample gas.

Operatively associated with the viscosity-effusion bridge B, is a gas absorbing medium such as a carbon dioxide remover R, which may be filled with a suitable absorbent such as "Ascarite," which is a sodium hydrate asbestos absorbent. Although an absorbent of this type is preferred, other well known materials for absorbing carbon dioxide may be used. The remover R may be provided with a novel two-way by-pass valve V (Figs. 1 and 3) which may be used to cut the remover in and out of circuit with the bridge without interrupting the flow of gas through the latter. An adjusting valve A (Fig. 2) is provided to adjust the manometer M to an arbitrary zero point on the scale S and a gauge G is connected to the chamber E to indicate the degree of vacuum maintained by the pump. Dust removers D, D' are associated, respectively, with each tube C, C'.

Referring more specifically to the drawing, the manometer M comprises a left hand arm 10 and a right hand arm 12, connected respectively to the T-pieces T, T'. A suitable reservoir 14 containing indicating liquid is connected to the manometer by a branch passage 16, and the amount of liquid may be increased or decreased by removal of a ground glass stopper 18 which is greased before reinsertion in the reservoir 14 to provide an air-tight seal therefor. The scale S is provided with two sets of graduations, one for indicating oxygen concentration and the other for indicating carbon dioxide concentration.

The standard gas, which may be air, enters through a tube or conduit 20 in which is located the adjusting valve A, passes through the dust remover D', the capillary tube C', the T-piece T', and the orifice O' into the evacuating chamber E. The sample gas enters through tubing or conduit 22 and by means of adjustment of the valve V may pass through a tube or conduit 24 and the carbon dioxide remover R into a branch tube or conduit 26 connected to tubing or conduit 28. If it is desired to have the sample gas by-pass the carbon dioxide remover, the valve V may be turned to the position shown in Fig. 1 and the sample gas to be analyzed then passes from this valve through a by-pass tubing or conduit 30 into the tubing 28. From the tubing 28, the sample gas passes through the dust remover D, the capillary tube C, the T-piece T, and the orifice O into the evacuating chamber E. Connected to the evacuating chamber is one end of a tubing 32 which is connected at its other end to the vacuum pump P, which should be capable of maintaining a vacuum in the chamber E of 25 inches of mercury or better. The gauge G is connected to the tubing 32 by means of a short piece of tubing 34.

A special check valve 36 is provided in the arm

10 in the differential manometer in order to prevent the liquid in the manometer from being withdrawn into the capillaries and orifices in case the end of the tubing 22 is accidentally shut off or restricted in any way. The reservoir 14 is large enough to hold all the liquid and thus prevent the liquid being drawn into the right hand arm 12 of manometer M if tubing 20 is restricted.

The adjusting valve A, shown in Fig. 2, comprises a body 40 in which is threadedly mounted a stem 42 surrounded by packing 44 held in place by a packing nut 46. Adjacent the lower end of the stem 42, the body 40 is formed with a chamber 48 communicating with an orifice 50. Co-axial with the chamber 48 is a small diameter central passage 52 terminating in a right angle passage 54. The stem 42 is formed with a conical seating portion 56 adapted to partially enter the passage 52 and engage the walls thereof at the intersection of this passage with the chamber 48 to restrict or prevent communication between the chamber 48 and the passage 52. Through adjustment of the stem 42 by means of a hand wheel 58, gas passing between the passage 54 and the orifice 50 through the chamber 48 may be throttled to any desired value in order to adjust the level of the fluid in the manometer tube to the proper point on the scale S.

To maintain continuity of operation of the apparatus when it is desired to change the indication from percentage oxygen to percentage carbon dioxide, or vice versa, and to prevent damage to the delicate parts of the apparatus, it is necessary to provide some means for cutting the carbon dioxide remover R into and out of circuit with the viscosity-effusion bridge B without interrupting the flow of gas through the bridge. If the flow of gas were suddenly initiated or suddenly interrupted, the liquid in the differential manometer might flow into the capillary tubing or be drawn through the orifices.

To prevent these conditions, a special two-way valve V, shown in Fig. 3, is provided to selectively by-pass the gas absorbing medium R. This valve is so designed that the flow of gas may be diverted from the inlet to either of two outlets without the valve passing through an "off" position.

Referring more specifically to Fig. 3 of the drawing, the valve V comprises a body 60 formed with a valve chamber 62, a packing chamber 64 and a partially threaded bore 66 connecting these chambers and forming a valve seat 68 at its intersection with chamber 62. The lower end of the valve body 60 is closed by a threaded plug 70 formed with a spring recess 72 communicating with the valve chamber 62 and with an outlet port 74. The upper or inner end of the plug 70 forms a second valve seat 76 in the chamber 62. A ball valve 78 is mounted in the valve chamber 62 and is resiliently urged in an upward direction by a spring 80 seated in the recess 72. The ball valve 78, in cooperation with either of the valve seats 68 or 76, controls communication between an inlet port 82 in the body 60 and either an outlet port 84 in the valve body or the outlet port 74 in the plug 70, respectively. The ball valve 78 is operated by means of a stem 86 threadedly engaging bore 66. On the outer end of stem 86 is an operating handle 88 and the inner end of the stem engages the ball valve 78. Suitable packing 90 is held in the packing chamber 64 around the stem 86 by a combined packing nut and valve mounting stud 92.

It will be observed readily that, irrespective of

the position of ball valve 78, gas may always flow from inlet port 82 to either of the outlet ports 74 or 84. At no time during the movement of the ball valve from one seat to the other is the flow of gas through the valve chamber interrupted.

The method of operating the above described apparatus to indicate the oxygen concentration in the sample gas is as follows: The stopper 18 is removed and manometric liquid is added to the reservoir 14 until the level of the liquid reaches a point on the oxygen scale corresponding to 21%, which is the approximate proportion of oxygen in normal air. The stopper 18 is then greased and replaced to seal the manometer M. The vacuum pump P, connected to the tubing 32, is then started and the valve V is adjusted so that the tubing 22 communicates with the remover R through the tubing 24.

In order to permit proper adjustment of the liquid level with respect to the scale S, the standard gas side of the apparatus is constructed to permit a slightly greater flow of gas than is permitted by the sample gas side. Thus, when the vacuum pump is started, and air enters both sides of the bridge at atmospheric pressure or at equal pressures approximately atmospheric, the liquid level will first rise and then fall as the maximum vacuum is obtained. The liquid level is then adjusted to the 21% oxygen mark through manipulation of the adjusting valve A. The vacuum should be maintained between 25 and 30 inches of mercury to assure stable indications.

When the above adjustments have been made, the tubing 22 is connected by means of a suitable length of tubing of rubber or other material to the oxygen tent or room containing the sample gas to be analyzed as to oxygen content. Within a minute, the manometric liquid level will rise to a point indicative of the percentage concentration of oxygen in the sample gas. The apparatus may now be left running and will give a continuous indication of the oxygen concentration in the sample gas.

It will be noted that the carbon dioxide is removed from the sample gas, and thus the indicated oxygen percentage is that of the sample gas minus the carbon dioxide content. However, if the percentage of carbon dioxide is small, the indicated oxygen percentage may be accepted as correct for all practical purposes.

To condition the apparatus for indicating the carbon dioxide concentration, the vacuum pump is stopped. Next, the tubings 20 and 22 are connected by means of a T-piece to a suitable length of tubing and this is inserted in the tent or room containing the sample gas. After the valve V has been adjusted to permit the gas to by-pass the remover R, the vacuum pump is restarted and the liquid level in manometer M adjusted to the zero point on the carbon dioxide scale by manipulation of the adjusting valve A. The valve V is now adjusted to place the remover R in circuit with the manometer M, and the liquid level will then indicate the carbon dioxide concentration.

In effect, the zero adjustment is made when the same gas is passing through both sides of the viscosity-effusion bridge B, and enters both sides of the bridge at equal pressures approximately atmospheric. When the carbon dioxide remover R is placed in circuit, the bridge compares the mixture containing the carbon dioxide with the same mixture minus the carbon dioxide. Thus,

the liquid level in the manometer indicates the carbon dioxide percentage. This indication is independent of the relative volumes of oxygen and nitrogen in the mixture.

To recondition the apparatus to indicate oxygen concentration, the T-piece is removed from tubings 20 and 22 and the liquid level is adjusted to the 21% point on the oxygen scale through the medium of valve A, with air entering tubes 20 and 22. When tubing 22 is inserted in the sample gas, the apparatus will indicate the oxygen concentration.

While the effect of the capillary length on the sensitivity is small, within certain limits, there is a definite ratio between the orifice diameter and the capillary diameter which will assure optimum sensitivity. Thus, the orifice diameter should be three-quarters of the capillary diameter, and the pressure at the outlet of the capillary about one-half the inlet pressure. As a specific example, with each tube C, C' having a uniform diameter of 0.5 mm. and a length of 9 inches, and with the orifice having a diameter of 0.375 mm., the sensitivity of the apparatus for the oxygen indication is 2.3 mm. and for the carbon dioxide indication is 13 mm. The sensitivity is given as the change in level for a 1% change in composition. The accuracy of indication is, respectively, $\pm 2\%$ and $\pm 0.5\%$ for oxygen and carbon dioxide and is not affected, within these limits, by variations in the humidity of the air. Furthermore, if both the standard gas and the sample gas are approximately equal in temperature, a variation of a few degrees between the respective gas temperatures will not affect the accuracy within the above limits. The indications are not affected by the degree of vacuum provided a minimum vacuum of 25 inches of mercury is maintained. No air leak to maintain the vacuum at a definite value is necessary provided the conditions of critical flow through the orifices are maintained.

In order that the accuracy of indication may be independent of changes in barometric pressure, interchangeable scales S may be provided, each corresponding to a definite barometric pressure. Since the effect of a change in barometric pressure is to displace the entire calibration curve as a unit, it is only necessary to select the scale which gives the correct reading for 100% oxygen content at the given barometric pressure. The apparatus is thus suitable for use at any altitude.

The only handling of chemicals required is the occasional replacement of a cartridge type unit of "Ascarite," or other suitable absorbent for carbon dioxide, in the carbon dioxide remover R. Furthermore, all elements of the apparatus except the vacuum pump may be mounted in a simple cabinet and easily transported to different locations.

While the apparatus is intended to give a continuous indication of the oxygen concentration and only intermittent indications of the carbon dioxide concentration, it can be used, equally well, to give a continuous indication of the carbon dioxide content. Furthermore, it is apparent that, while the apparatus is designed primarily to indicate oxygen and carbon dioxide concentrations, by a suitable change of scales it may be used to indicate concentrations of other constituents of a sample gas.

While a specific embodiment of the invention has been illustrated and described in detail, it will be obvious that the invention may be otherwise embodied and certain dimensions and in-

terrelations of parts changed so long as the objects of the invention are attained.

What is claimed is:

1. A gas analyzer comprising, in combination, two comparison tubes, each having a capillary portion; a conduit connected to the inlet side of each tube and extending respectively to a source of standard gas and to a source of gas under test; a chamber connected to the outlet sides of said tubes; an orificed plate in each tube on the downstream side of the capillary portion; a differential manometer having its arms connected, respectively, to each of said tubes between the capillary portion and the orificed plate; exhausting apparatus connected to said chamber; a gas absorbing medium interposed in the conduit which extends between said source of gas under test and its associated comparison tube; and means operatively associated with said last-named conduit for selectively by-passing said gas absorbing medium without interrupting the flow of gas through said associated comparison tube.

2. A gas analyzer comprising, in combination, two comparison tubes, each having a capillary portion; a conduit connected to the inlet side of each tube and extending respectively to a source of standard gas and to a source of gas under test; a chamber connected to the outlet sides of said tubes; an orificed plate in each tube on the downstream side of the capillary portion; a differential manometer having its arms connected, respectively, to each of said tubes between the capillary portion and the orificed plate; exhausting apparatus connected to said chamber; means, connected in the conduit extending between said source of gas under test and its associated comparison tube, for removing a given constituent of said gas under test; means, operatively associated with the conduit extending between said source of gas under test and its associated comparison tube, for selectively by-passing such removing means; and means operatively associated with said manometer for indicating the percentage of two different constituents of said gas under test.

3. A gas analyzer comprising, in combination, two comparison tubes, each having a capillary portion; a conduit connected to the inlet side of each tube; means for connecting each of said conduits to a source of gas under test; a chamber connected to the outlet sides of said tubes; an orificed plate in each tube on the down-stream side of the capillary portion; a differential manometer having its arms connected, respectively, to each of said tubes between the capillary portion and the orificed plate; exhausting apparatus connected to said chamber; a gas absorbing medium interposed in one of said conduits; and means operatively associated with said one conduit for selectively by-passing said gas absorbing medium without interrupting the flow of gas through the associated comparison tube.

4. A gas analyzer comprising, in combination, two comparison tubes; each having a capillary portion; a first conduit connected to the inlet side of one comparison tube; a second conduit connected to the inlet side of the other comparison tube and to a source of gas under test; means for connecting said first conduit to either said source of gas under test or a source of standard gas; a chamber connected to the outlet sides of said tubes; an orificed plate in each tube on the down-stream side of the capillary portion; a differential manometer having its arms connected, respectively, to each of said tubes between the

capillary portion and the orificed plate; exhausting apparatus connected to said chamber; a gas absorbing medium interposed in said second conduit; means operatively associated with said second conduit for selectively by-passing said gas absorbing medium; and an interchangeable scale associated with said manometer and calibrated to indicate selectively the percentages of two constituents of said gas under test.

5. A gas analyzer as claimed in claim 4, in which such by-pass means comprises a valve interposed in the conduit between said gas absorbing medium and said source of gas under test for selectively by-passing said gas absorbing medium.

6. A gas analyzer comprising, in combination, means for comparing a gas under test with a standard gas; a first conduit extending between said means and a source of standard gas; a second conduit extending between said means and a source of gas under test; a gas absorbing medium interposed in said second conduit between said means and said source of gas under test; and means, including a valve interposed in said second conduit between said medium and said source of gas under test and a by-pass conduit connected to said valve and to said second conduit between such comparison means and said medium, to by-pass said medium selectively without interrupting the flow of gas from said source of gas under test to said gas comparison means.

7. The gas analyzer claimed in claim 6, in which said valve comprises a valve chamber having a plurality of ports adapted to be connected respectively to that portion of the second conduit extending to said source of gas under test, that portion of the second conduit extending to said gas absorbing medium and said by-pass conduit and a valve member in said chamber operable to close selectively said ports connected to said gas absorbing medium and said by-pass conduit, respectively, without interrupting the flow of gas from said source of gas under test to said gas comparison means.

8. The gas analyzer claimed in claim 6, in which said valve comprises a valve chamber former with an inlet port connected by that portion of the second conduit extending to said source of gas under test and two outlet ports connected, respectively, to that portion of the second conduit extending to said medium and to said by-pass conduit, and means disposed in said valve chamber for selectively closing either of said outlet ports without substantial interruption of the flow of gas from said inlet port through said chamber to said gas comparison means.

9. A method of continuously analyzing a gas under test which comprises separately and continuously withdrawing two samples from a source of gas under test, chemically absorbing one constituent of said gas from one of the samples, and comparing the viscosity and density of such sample with the viscosity and density of the other of the samples to indicate the percentage concentration of said chemically absorbed constituent in said gas under test.

10. A method of indicating the percentage concentration of a given constituent of a gas under test which comprises passing a standard gas through both sides of a viscosity-effusion bridge and adjusting said bridge to indicate the normal percentage concentration of said given constituent in said standard gas; then continuously passing said standard gas through one side of said bridge, and a sample from a source of said gas

under test through the other side of said bridge, while chemically absorbing a different constituent of said gas under test before said gas under test enters said bridge; and comparing the viscosity and density of said standard gas with the viscosity and density of said gas under test to indicate the percentage concentration of said given constituent in said gas under test.

11. A method of continuously indicating the percentage concentration of a given constituent of a gas under test which comprises passing samples of said gas through both sides of a viscosity effusion bridge; adjusting said bridge to indicate a zero percentage concentration of said given constituent; then chemically absorbing said given constituent from the sample of gas passing through one side of said bridge without interrupting the continuous flow of gas through said bridge; and comparing the viscosity and density of one sample with the viscosity and density of

the other sample to indicate the percentage concentration of said given constituent in said gas under test.

- 5 12. A gas analyzer comprising, in combination, a viscosity-effusion bridge provided with means for indicating the percentage concentrations of two constituents of a gas under test; an exhausting mechanism connected to the outlet side of said bridge; means for connecting one side of
10 said bridge to a source of gas under test; means selectively operable to connect the other side of said bridge to said source of gas under test and to a standard gas; a gas absorbing medium in circuit with said one side of said bridge; and
15 means, operatively associated with said means for connecting one side of said bridge to a source of gas under test, for selectively bypassing said gas absorbing medium without affecting the flow of gas through said bridge.
